PERMANENT WAVING APPARATUS

Daniel Lakenbach, Valley Cottage, N. Y.

Original application August 18, 1933, Serial No. 685,684. Divided and this application April 30, 1934, Serial No. 723,021

3 Claims. (Cl. 219—24)

The invention relates to an apparatus to be used in imparting a so-called "permanent wave" to human hair. More particularly the invention relates to a heating unit of novel construction.

5 The present application is a division of my application, Serial No. 685,684, filed August 18, 1933, Patent No. 1,968,773, July 31, 1934.

The primary object of the invention is to provide an internal heating unit which is adapted to 10 be removably inserted into a curling rod or mandrel provided with an axial bore to receive such heating unit.

15 Various other objects and the advantages flowing therefrom will be apparent in conjunction with the following description of my novel device.

In the accompanying drawing forming part of this specification I have shown a particular embodiment of my invention by way of illustration rather than by way of limitation. In such drawing

20 Fig. 1 is a plan view of my novel removable internal heating unit;

Fig. 2 is a longitudinal section through the heater unit;

25 Fig. 3 is a section on the line 11—11 of Fig. 2; and

Fig. 4 shows my novel heating unit inserted in the bore of a spiral curling rod with the latter applied to a protector.

30 Referring more particularly to the drawing, in which similar reference characters identify similar parts in the several views, my novel removable internal heating unit, adapted for use with a Croquignole curling rod or with a "spiral" rod, 35 consists in an outer shell 33 of metal or similar heat-conducting material, having an expansion end 34 formed by longitudinal slits 35 provided at opposite faces of the shell. The purpose of providing this type of expansion end is to obtain the necessary friction, when the heating unit has 40 been inserted into the bore of the curling rod, to retain the heating unit practically at any depth within the curling rod. A pull knob 36 of a heat resisting material, such as a phenolic condensation 45 product and preferably provided with a knurled surface 37, is fixed to the outer end of the heating unit within which the lead cords 38, 39 terminate.

The heating element of my novel heating unit 50 comprises a coiled resistance 40 housed within two parallel bores 41, 42 in a rod 43 which is secured within the heater shell 33. The rod 43 is made of a highly heat-resistant or refractory material, for instance, that known as lava.

The assembly of the heating unit is as follows: 55 The coiled resistance elements 40 are passed

through both bores 41 and 42 in the lava rod 43 and are joined at the upper extremity of the lava rod, for instance, by twisting, a sealing element 44 of an insoluble material, for instance, porcelain, being applied over the joined ends of the coiled resistance to secure a moisture and air-tight sealing. The lower extremity of the lava rod is cut away, as shown at 45, so as to leave a tongue or separating wall 46 projecting beyond the cut-away ends of the lava rod. The ends of the lead cores 10 38 and 39 are then joined to the free ends of the coiled resistance element 40, asbestos being applied within the upper portion of the recess 47 and there held in place by a sealing material. A brass washer 48 is then put in place by a press 15 fit so as to seal the recess 47, a few of the turns of the spring 49 above the washer being larger than the remaining turns of the spring so as not to pull through the washer. In this manner the spring is securely anchored in the washer. 20

It will be noted that the outer shell 33 is circumferentially flared at the bottom extremity thereof as at 50 so as to securely fasten such shell within the pull knob 36. Preferably a flat surface is also ground on one side of the flared end 50 of the 25 shell 33 so as to prevent the turning of such shell within the pull knob in which it has been anchored.

It will be noted from Fig. 2 that the lava rod 43 when inserted into the heater shell 33 stops short of the end thereof, thereby providing an air 30 gap which serves to keep the protector cool and acting as an insulating gap due to the fact that there is no transfer of heat by conduction through the upper open end of the shell 33.

The removable internal heating unit just described is adapted for use not only with the curling rod employed in the Croquignole method of permanent waving, particularly shown and described in my copending application above referred to, but also for use with the spiral method, 40 its application to the latter method being illustrated in Fig. 4. While the identical form of heating unit is utilized in carrying out such method, the curling rod is necessarily of different construction, comprising the rod 51 having an axial bore 52 to accommodate the heating unit and a head 53 rotatable in one direction and applied to the protector 54 of the type shown and described in my application Serial No. 674,786, filed June 8, 1933. Riding over the curling rod is a 50 butterfly clamping element 55 which may be used to tighten the tress 56 about the curling rod after such tress has been wound thereon in the well-known manner.

While I have described a specific embodiment 55

of my invention, it is obvious that various modifications therein, particularly in the configuration and arrangement of the various parts may be made without departing from my invention.

5 I claim:

1. An internal heating unit for use in permanent waving, adapted to be removably inserted within a curling rod, comprising an outer shell, an inner rod having a plurality of bores running the length thereof, a heating element comprising a coiled resistance extending through said bores, a pull knob within which said outer shell is anchored and lead cords connected to the free ends of said heating element and anchored within said pull knob.
- 10 2. An internal heating unit for use in permanent waving, adapted to be removably inserted within a curling rod, comprising an outer shell having an expandible end, an inner rod of a re-

fractory material having a plurality of bores running the length thereof, a heating element comprising a coiled resistance extending through said bores, a pull knob within which said outer shell is anchored and lead cords connected to the free ends of said heating element and anchored within said pull knob.

- 15 3. An internal heating unit for use in permanent waving, adapted to be removably inserted within a curling rod, comprising an outer shell, an inner rod having a plurality of bores running the length thereof, a heating element comprising a coiled resistance extending through said bores, joined and sealed together at one end of said inner rod, a pull knob within which said outer shell is anchored and lead cords connected to the free ends of said heating element and anchored within said pull knob.
